UNITED STATES PATENT OFFICE.

DAVID H. ENGELSON, OF BROOKLYN, NEW YORK.

DESIGN FOR A RADIO DIAL ESCUTCHEON PLATE.

Application filed May 11, 1927. Serial No. 21,933. Term of patent 3½ years.

To all whom it may concern:

Be it known that I, DAVID H. ENGELSON, a citizen of the United States, residing at Brooklyn, in the county of Kings and State of New York, have invented a new, original, and ornamental Design for a Radio Dial Escutcheon Plate, of which the following is a specification, reference being had to the accompanying drawing, forming a part thereof.

The figure is a perspective view of a radio dial escutcheon plate embodying my new design.

I claim:—

The ornamental design for a radio dial escutcheon plate as shown.

DAVID H. ENGELSON.
